UNITED STATES PATENT OFFICE

160,701

CANDY DISH

Bruno Fortuna, North Bergen, N. J.

Application May 19, 1949, Serial No. 2,756

Term of patent 3½ years

(Cl. D44—10)

To all whom it may concern:

Be it known that I, Bruno Fortuna, a citizen of the United States, residing in North Bergen, county of Hudson, and State of New Jersey, have invented a new, original, and ornamental Design for a Candy Dish, of which the following is a specification, reference being had to the accompanying drawing, forming part thereof.

In the drawing:

I claim:

The ornamental design for a candy dish, as shown.

BRUNO FORTUNA.
